CHARLES F. WALL AND FREDERICK HARKER, OF PHILADELPHIA, PENNSYLVANIA.

DOUBLE-RADIUS GRINDING-MACHINE.

1,140,421.

Specification of Letters Patent. Patented May 25, 1915.

Application filed May 2, 1914. Serial No. 835,852.

To all whom it may concern:

Be it known that we, CHARLES F. WALL and FREDERICK HARKER, citizens of the United States, and residents of the city of Philadelphia, county of Philadelphia, State of Pennsylvania, have invented certain new and useful Improvements in Double-Radius Grinding-Machines, of which the following is a specification.

10 Our invention relates to machines adapted to be used in the grinding of concaved surfaces having different radii of curvature in different planes through such surfaces at right angles to each other.

15 One object of our invention is to provide means whereby parts of the apparatus embodying the same may be quickly proximate to such positions relatively to each other as it is desired they shall occupy during the grinding operation.

A further object of our invention is to provide a machine which is simple in construction, consisting of few parts, and which may be cheaply and economically constructed.

25 Although our invention may be used for operating upon a variety of kinds of work we have illustrated the same as it may be used to grind the concaved surface of a tool 30 to be used for the grinding of the outer or front surface of a toric lens.

Other objects and advantages than those above stated will be set forth in the detailed description of our invention which follows 35 or will be apparent therefrom.

In the accompanying drawings we have illustrated one form of a convenient embodiment of our invention but it will be understood that the same is susceptible of being 40 embodied in other forms and that changes in the details of construction may be made without departing from the scope of our invention.

In the drawings: Figure 1 is a side elevation of a machine embodying our invention; Fig. 2 is a view partly in top plan and partly in horizontal section; Fig. 3 is a front end elevation thereof; Fig. 4 is a transverse sectional view on the line 4-4 of Fig. 3; 50 Fig. 5 is a sectional view through a tool which has been operated on by the machine embodying our invention; and Fig. 6 is a view showing a section of the same tool taken at right angles to the view shown in 55 Fig. 5.

In the drawings, 1 designates the top por-

tion of a pedestal upon which a bed 2 is supported. The bed 2 is provided with pedestals 3, one of which is shown in elevation in Fig. 1 of the drawings, which pedestals are provided with bearings 4 and 5 at their upper ends in which a revoluble shaft 6 is mounted. The shaft is provided with a band wheel 8, situated intermediate the bearings 4 and 5, by means of which the shaft 6 may be driven from any suitable source of power.

10 designates a grinding wheel of emery or other suitable material which is removably secured to the end of the shaft 6 between the clamping plates 11 and 12 by means of a nut 13. The grinding wheel is made removable so that wheels of different diameters may be employed for operating upon the work.

The bed 2 is provided with forwardly projecting portions 14 and 15 upon which a rectangular bar 16 is mounted. At its forward end the said bar is located in a recess 17 formed in the projecting portion 15 of the bed 2 so that the top of the bar 16 is flush with the top surface of the projecting portion 15 thereby making a smooth surface which is necessary as will hereafter appear.

The work 18, which in the construction 85 illustrated consists of a tool to be employed in the manufacture of toric lenses, is provided with a shank 19 which projects through a split sleeve 20 in the upper end of a standard 21. The said shank is clamped in 90 said sleeve by means of a screw-threaded bolt 22. If after the work has been partially completed it is removed from the split sleeve 20 and it is desired to replace the same it is necessary that it be replaced in exactly the 95 same position it occupied previous to removal. To insure that it shall be so replaced the shank 19 is provided with a pointed depression 22^a which is engaged by the pointed end of a screw 23 which is secured in the 100 split sleeve 20 as shown. To remove the work from the sleeve 20 the screw-threaded bolt is loosened and the screw 23 is turned so as to withdraw its pointed end from the pointed depression 22^a. The work may then 105 be readily removed.

The standard 21 is adjustably secured upon an oscillatable bar 25 which is pivoted at 26 upon a block 27 which is slidably supported upon the bar 16. The base portion 110 of the standard 21 is provided with a hole 28 of the shape of the cross section of the

2
bar 25. The latter extends through said hole. A wedge or binding strip 29 is interposed between the edge of said bar and the side of said hole or opening 28 and is adapted to be clamped tightly against the said bar by means of a cam 30 upon a rotatable member 31 which is adapted to be turned by means of a handle 32. By turning the cam 30 in one direction the wedge 29 is loosened so that the standard 21 may be moved inwardly or outwardly upon the bar 25 to such position as may be desired and again clamped so that it may be held in such position. The block 27 is also provided with a hole extending therethrough through which the bar 16 extends and the said block may be clamped, if desired, in any position on such bar to which it may be adjusted by means of a cam upon the rotatable member 35, the latter being turned by means of the handle 36. The said cam operates against a wedge or binding strip 37 situated between the edge of the bar 16 and a side of the hole through the block 27. The pivot 26 consists of a shouldered screw-threaded member which is screwed into the upper side of the slide block 27. After the standard 21 has been adjusted upon the bar 25 to such position as may be desired with respect to the axis of oscillation of the said bar 25 it may be desirable and necessary to adjust the said standard together with the bar 25 and parts connected thereto either forwardly or backwardly so as to properly position the work with respect to the peripheral grinding surface of the grinding wheel 10. To accomplish such adjustment and positioning we have provided a rod 38 which is revolvably supported in projection 39 which extends downwardly from the projecting portion 15 of the bed 2.

41 designates a collar secured upon the rod 38, which collar is seated against the projection 39 so as to prevent forward displacement of the rod 38. Movement in the opposite direction of said rod is prevented by the fact that the inner end of the hub 42 of the handle 43 which is secured to the outer forward end of the rod 38 rests against the opposite side of the projection 39. The forward end of the rod is screw-threaded, as indicated at 45, and is in engagement with a projection 46 which is connected with and extends downwardly from the slideable block 27. It will be seen, therefore, that when the cam 35 is turned so as to loosen the wedge which is adapted to be clamped against the side of the bar 16 the slide block 27 and bar 25 may be adjusted either forwardly or backwardly upon the bar 16 by turning the screw-threaded rod 38, such rod being turned by the handle 43.

For the purpose of approximating the position to which the standard 21 should be adjusted upon the bar 25 we have provided

the following instrumentality, to wit, a rod or bar 49 provided with a scale 50 to indicate the length of the portion of the rod or bar 49 which projects inwardly from the end of the sleeve 51 in which it is adjustably secured, said sleeve being supported upon the upper end of a standard 52 carried by the slide 27. The said sleeve is provided with a projecting circular portion 53 which is pivoted in an opening formed in a projecting or over-hanging portion 54 of the standard 52. The rod 50 is adapted to be clamped in any position to which it may be adjusted in the sleeve by means of a binding screw 55. The axis of the pivot 53 which is the axis of oscillation of the sleeve 51 is in exact alignment with the axis of oscillation of the bar 25 and also is in exact alignment with the inner end of the sleeve 51. We have provided laterally extending projections or wings 57 upon the base of the pedestal 21 for the purpose of increasing the width of the base or portion of the said pedestal which slides over or upon the projecting portion 15 of the supporting bed 2. This is desirable for the purpose of preventing, as far as possible, the vibration or wabbling of the pedestal 21 when the latter is oscillated during the operation of the machine.

Having now described the construction of the apparatus we shall describe the operation of the same. The work to be operated upon is secured in the split sleeve 20 at the upper end of the standard 21. The rod 49 is then adjusted so that it projects forwardly from the sleeve a distance equal or substantially equal to the radius of one of the curves of the concaved surface which it is desired to grind upon the work or tool 18. This distance may be ascertained from the scale 50 upon the said rod or bar 49. When the said rod or bar has been adjusted to the position desired it is clamped in such position by means of the binding screw 55. The standard 21 and slide 27 are then adjusted toward or from each other so that the forward end of the bar 49 contacts with the inner or confronting surface of the work to be operated upon. Thereafter, the bar 49 may be turned into such position that it does not interfere with the operation of the machine by contacting with the grinding wheel 10 or with the work as it is oscillated. The standard 21 after having been thus positioned is clamped by means of the wedge 29 and cam 30 to the bar 25 and the rod 38 is then rotated so as to adjust the slide block 27 and the oscillatable bar 25 forwardly or backwardly so as to bring the work 18 into operative position with respect to the grinding wheel 10.

During the grinding operation the bar 25 and the standard 21 fixedly clamped thereto are fed or adjusted toward the grinding tool from time to time in order to cut away

the work to the extent desired. Between such adjustments, however, the work is oscillated about the pivot 26, such oscillation being effected by means of the handle 61 upon the standard 21, the operator taking hold of the handle and moving the said standard 21 and the front end of the bar 25 about the axis of the pivot 26 and at right angles to the plane of the grinding wheel 10.

10 The radius of curvature cut by such wheel in planes at right angles to the plane of said grinding wheel will depend upon and will be equal to the distance between the axis of the pivot 26 and the arc of movement of the work 18. The curvature in the opposite direction, that is, in planes parallel to the plane of the grinding wheel 10, will depend upon and will be governed by the diameter or radius of the said grinding wheel, such curvature being of the same radius as the radius of the wheel.

During the operation of the machine the wedge 37 should be clamped against the bar 16 with the tightness necessary to create sufficient friction to prevent accidental displacement, due to vibration of the machine, of the sliding block 27 and the parts connected thereto during the operation of the machine. Preferably such friction should 30 not be sufficient to prevent adjustment of the slide block 27, the bar 25 and the standard 21 rearwardly by the turning of the rod 38 so as to feed the work against the peripheral edge of the grinding tool 10.

35 We claim:—

1. The combination of a revoluble grinding wheel, an oscillatable member pivoted in rear of and in the plane of said grinding wheel, a work support secured upon said oscillatable member in front of said grinding wheel and means whereby said work support may be adjusted toward or from said grinding wheel.

2. The combination of a revoluble grinding wheel, an oscillatable member pivoted in rear of and in the plane of said grinding wheel, a work support secured upon said oscillatable member in front of said grinding wheel, means whereby said oscillatable member may be adjusted so as to move the said work support toward or from the said grinding wheel without altering the radius of oscillation of the said work support and means whereby said work support may be independently adjusted upon the said oscillatable member toward or from the said grinding wheel.

3. The combination of a revoluble grinding wheel, an oscillatable member pivoted in rear of said grinding wheel, a work support secured upon said oscillatable member in front of said grinding wheel, and means whereby said oscillatable member may be manually oscillated.

4. The combination of a revoluble grind-

ing wheel, an oscillatable bar pivoted in rear of and in the central plane of the said grinding wheel, a work supporting member secured upon said oscillatable bar in front of said grinding wheel, and means whereby said work supporting member may be adjustably secured on said bar in operative relation to said grinding wheel, and means whereby the said oscillatable bar may be oscillated.

5. The combination of a revoluble grinding member, a stationary bar, a slideable member supported on said bar, a work supporting member having pivotal connection with the said slideable member, and means for adjusting the said slideable member longitudinally of the said stationary member.

6. The combination of a stationary bar, an adjustable member secured thereon, a work carrier having pivotal connection with said member, means supported upon said member for locating said carrier and the work thereon in the position desired with respect to the axis of the pivot of said pivotal connection and a grinding member positioned between the said adjustable member and the said work support.

7. The combination of a stationary bar, a slideable member adapted to be secured in different positions upon said bar, a member having pivotal connection with said slideable member, a work support secured upon said pivotal member, and means supported upon said slideable member for locating the work upon the said support in the position desired with respect to the pivot of said pivotal connection, and a grinding member for grinding said work.

8. The combination of a stationary bar, a slideable member on said bar, a bar pivotally secured to said slideable member, a work support adjustably secured to said pivotal bar, a pivoted measuring device carried by said slideable member, the axis of said pivoted measuring device being in alinement 105 with the axis of the pivot of the said pivoted bar.

9. The combination of a stationary bar, a slideable block secured thereon, a member pivoted to said block, a work support having adjustable connection with said member, a standard secured to said block, a measuring device pivotally supported upon said standard, the axis of its pivot being in alinement with the axis of the pivot of the said pivoted member, the purpose of the said measuring device being to position the work at the desired distance from the axis of the pivot of the said pivoted member for the purposes described.

10. The combination of a revoluble grinding wheel, a stationary supporting bar, a slide block on said bar, a member pivoted to said slide block, a work support on said pivoted member, and adjustable means for position-

- ing the work upon said work support a desired predetermined distance from the axis of the pivot of the said pivoted member.
11. The combination of a removable revoluble grinding member, an oscillatable work support for supporting the work in operative relation to said grinding member, and means for ascertaining the position at which it is desired to locate the work with respect to the axis of oscillation of the work support.
12. The combination of a revoluble grinding member, an oscillatable work support for supporting the work in operative relation to said grinding member, means for ascertaining the position at which it is desired to locate the work with respect to its axis of oscillation, and means for positioning the work support and the work carried thereby in operative relation to the said grinding member.
13. The combination of a revoluble grinding wheel, an oscillatable work support, a pivotally supported adjustable member for positioning the work on said support the desired distance from its axis of oscillation, and a manually operable member for adjusting the work into operative relation to said grinding wheel.
14. The combination of a revoluble grinding member, an oscillatable work support,
- means for positioning the said work support and the work carried thereby the desired distance from its axis of oscillation, means for thereafter adjusting the work into operative relation to said grinding wheel and for thereafter feeding the work to the said grinding wheel at intervals.
15. The combination of a revoluble grinding wheel, a stationary guide bar, a slidable member on said bar, a bar having pivotal connection to said slidable member, a work support adjustable upon the pivoted bar, a pivoted measuring device for positioning the said work support and the work carried thereby upon the said pivoted bar at the desired distance from the axis of the pivot of said bar, means for clamping the said work support to the pivoted bar at such position, and means for adjusting the said slidable member of the said guide bar so as to move the work into operative relation with respect to said grinding wheel.

In testimony that we claim the foregoing as our invention we have hereunto signed our names this 1st day of May, A. D. 1914.

CHARLES F. WALL.
FREDERICK HARKER.
